RING LAPPING MACHINE

Charles A. Fulmer, Fort Thomas, Ky.

Application May 2, 1944, Serial No. 533,780

7 Claims.

(Cl. 51—26)

This invention relates to lapping machines and is directed to improvements in a machine of this character which is particularly useful in accurately adapting a set of piston rings for immediate use in its particular motor cylinder.

It is an object of the invention to provide a small, simplified machine which has an efficient ring-lapping movement wherein the replacement rings are reciprocated within their actual motor cylinder and during said reciprocation provides said rings with a rotary feed stroke movement, and a non-rotary return stroke movement.

Another object of the invention is to provide in an alternate rotary and non-rotary reciprocating mechanism for a piston ring lapping machine, a means whereby the movement of the ring carrying member traverses a different portion within the cylinder with each cycle of its movement.

It is a further object of the invention to provide in a lapping machine a threaded control means which is rotatably journaled on a machine base for mounting a reciprocating threaded, tool-carrying member, an overrunning clutch being interposed between the base and the control means for precluding rotation of said means to permit rotation of the tool carrying means in one phase of its movement and to also provide a second overrunning clutch which precludes rotation of the tool-carrying means and permits rotation of the control means in the opposite phase of movement of the tool-carrying means.

Other objects of the invention will be apparent from the following specification and drawings which describe and illustrate the preferred embodiment of my invention and in which:

Fig. 1 is a side elevational view of my ring lapping machine, a motor cylinder and its mounting standard being shown in central cross-section.

Fig. 2 is a plan view of the machine, parts thereof being shown diagrammatically.

Fig. 3 is an enlarged cross-sectional view taken on line 3—3 of Fig. 2.

Fig. 4 is a cross-sectional view taken on line 4—4 of Fig. 3.

Fig. 5 is a cross-sectional view taken on line 5—5 of Fig. 3.

The machine illustrated in the drawings is adapted to lap a set of new or replacement rings into the actual motor cylinder 7 in which they are to be subsequently used. This cylinder may be commercially used in aviation engines of the radial type and is provided with a bolting flange 8 for mounting it on the blocks of said engines. The machine is provided with a base 9 and has

an integral standard 10 positioned at the end thereof. This standard has a circular opening 11 formed therein for receiving the inner skirt portion 12 of the cylinder 7. As shown in Figs. 5 and 2 adaptor rings 13 of various internal bores may be inserted in the circular opening 11 in the standard so that cylinders having various diameters may be securely mounted in said standard.

Speed clamps 14 are provided to secure the 10 bolting flange 8 of the cylinder to the standard, said clamps comprising a lever 15 having a flange 16 engaging portion 16, a mounting portion 17 and a cam 18 pivoted to its outer end. The cam is provided with a handle 19 which upon rotation 15 turns the cam surface against an extended portion 20 on the standard to thereby tilt the lever and clamp the inner end 16 of the lever to the flange.

A ring carrying member is provided with a 20 spirally formed surface which may take the form of a shaft 21 which as shown in Fig. 4 is substantially square in cross-section; the four flat sides of said shaft forming a spiral speed screw which extends the entire length of said shaft. As indicated in Figs. 1 and 2 each one of the spiral surfaces passes through an arc of 180° as they traverse the longitudinal distance of the shaft. A ring mounting member 22 is fixed coaxially on the outer end of the shaft by means of a nut 23 25 which cooperates with a threaded stud 230 extending from the shaft end, said member being provided with a number of peripheral grooves 24 for receiving the rings 6. The ring mounting member is a duplicate or facsimile of the motor piston for the cylinder 7 and for all practical purposes a discarded piston of the proper specification may be used by drilling a centrally disposed hole through its web portion for receiving stud 230. The piston is also provided with a number of thin pins 240 which extend from the bottom of the grooves 24 and are adapted to engage the adjacent edges of the split piston rings held in said grooves to preclude rotation of said rings relative to the piston when it is 30 reciprocated within the motor cylinder 7.

This ring carrying member is guided for rectilinear movement in a bearing block 25 mounted on the base by means of legs 26 and 27. The bearing block has a cylindrical opening 28 formed 35 therein which is disposed coaxially with the shaft 21 and the cylinder opening 11 formed in the standard 10. As most clearly shown in Figs. 3 and 4 a control means takes the form of a sleeve 29 rotatably journaled in the opening 28 and has 40 formed through its axial center a spiral thread 45

30 for slidably engaging the threaded shaft 21 of the ring carrying member. The sleeve is held against axial movement within the block by a shoulder 31 and an oppositely disposed threaded end portion 32 which cooperates with a lock nut 33. A circular oil chamber 300 is formed in the block around the sleeve 29, a wick 301 passing through said sleeve to carry oil from the chamber to the spiral shaft 21.

The ring carrying member is adapted for rectilinearly directed reciprocating movement within the cylinder 7 by means of a suitable motor 34. This motor takes the form of an elongated cylinder 35 mounted at its inner end on a block 36 fastened to the base. This cylinder has a piston 37 movable therein which is connected to a piston rod 38. The free end of the rod is rotatably connected to the inner end of the spiral shaft 21 and as shown in Fig. 3, said inner end of the shaft is provided with an internally threaded portion 39 which terminates at its inner end in a circular shallow opening 40. The rod 38 is formed with a reduced end portion 41 having a circular shoulder 42 positioned on its extremity. This shoulder is fitted in the shallow opening 40 in the shaft 21 and is in abutment with a thrust bearing disk 44 disposed in the bottom of said opening. The shoulder 42 is rotatably held in the opening 40 against axial movement by means of a split nut 45 having two identical portions 46 and 47 which form a central opening 48 between them for receiving the reduced portion 41 of the rod and are provided with exterior threads for cooperation with the interior threads 39 formed in the rod 21.

The reciprocating motion is imparted to the motor piston 37 by means of a suitable hydraulic system provided with a motor driven pump 49 the intake port of which is connected to sump tank 50 by a pipe line 51. The pressure line 52 for the pump is connected to a conventional two-way valve 53 mounted on the base 9 and has interposed therein a volume control valve 54 conveniently positioned on the base. A pressure relief valve 520 is connected in the pressure line 52 between the pump and the volume control valve and is adapted to automatically bleed off and return to the sump tank, by line 521, pressure fluid delivered by the pump in excess of the pressure setting of the volume control valve. Pressure lines 55 and 56 are connected to the two-way valve and communicate with suitable ports formed in the inner and outer ends of the cylinder 35 respectively. An exhaust line 57 connects the two-way valve and the sump tank. The pipes 55 and 56 are alternately and simultaneously constituted pressure and exhaust lines for their respective cylinder ends by means of a control lever 58 which is actuated by a dog 59 extending from a control rod 60 mounted for rectilinear movement between the blocks 25 and 36. This rod carries two longitudinally adjustable stops 61 and 62 which determine the length of the stroke for the ring carrying member by engaging a shoulder 63 formed on the piston rod 38.

It will therefore be noted that the hydraulic motor imparts a succession of feed and return strokes to the ring carrying member and the means for imparting a rotary movement and a non-rotary movement to the member in its opposite reciprocating phases will now be described. The means for obtaining rotary movement of the member preferably during its feed stroke is obtained by an over-running clutch which comprises a clutch race 64 (Figs. 3 and 4) which is fixed to the sleeve 29 by key 65. The clutch is ro-

tatably mounted in a circular opening 66 formed in a clutch plate 67 the latter being fixed to the inner face of the block 25 by bolts 68. Two tangentially disposed passageways 69 and 70 are formed in the plate and are restricted at their inner ends by the interposition of the peripheral surface of the race 64. Clutch elements which take the form of balls 71 are disposed in the passageways and are urged toward the restricted portions by means of springs 72 held therein by threaded caps 73. Upon initiation of the feed stroke movement of the ring carrying member the sleeve 29 is held against counter-rotation imposed on it by the threaded screw by means of the clutching elements so that rotary movement is imparted to said member by the longitudinal movement of the spiral shaft through the rigidly held sleeve 29.

The return stroke of the ring carrying member is adapted to be a non-rotary one and to this end a second over-running clutch is interposed between the shaft and the base and comprises a concentric circular portion 74 formed on the inner end of the shaft 21 (Figs. 3 and 5). A clutch plate 75 is provided with a concentric circular opening 76 for rotatably receiving the circular portion 74 formed on the shaft 21 and has an upwardly extending arm 77 formed thereon for freely engaging a guide shaft 78 mounted between the blocks 25 and 36. This clutch plate is provided with restricted passageways 79 and 80 into which the circular portion on the shaft extends, suitable spherical clutching elements 81 being disposed therein and urged toward the restricted portion of said passageway by means of springs 82. During the return stroke of the ring carrying member these clutching elements lock the shaft against rotation and permit it to be drawn through the sleeve 29 causing the sleeve to rotate in an unclutched position relative to the elements 71. During the feed stroke the clutch elements 81 permit rotation between the clutch plate 75 and the circular portion 74 on the shaft 21.

It will therefore be noted that the control means for the ring carrying member is rotatably positioned on the base against axial movement and that the rotary movement of said member during its reciprocation is obtained by the cooperation of an over-running clutch interposed between the control means and the base and a second over-running clutch positioned between the member and the base. The over-running clutch for the sleeve control means is responsive to the counter-rotation of said sleeve when the ring carrying member begins its feed stroke and said clutch therefore locks the sleeve against rotation and the feed stroke actuation of the member imparts to it a rotary motion as the spiral portion thereof passes through said locked sleeve. During this feed stroke the second over-running clutch positioned at the inner end of the shaft remains inoperative to permit free rotation of said shaft. This second over-running clutch is locked in response to the initial movement of the return stroke and serves to lock the shaft relative to the clutch plate 75 which in turn is rectilinearly guided by the shaft 78, thereby precluding rotation of the ring carrying member during its said return stroke. When the second over-running clutch is operative the first over-running clutch is rendered inoperative and permits the control sleeve to rotate freely in its journal bearing as the spiral shaft passes through it in its rectilinear, non-rotary movement.

Both of the over-running clutches have a

slightly delayed responsive action to the initial movement of the ring carrying member in that a slight relative movement of the associated parts is necessary to lock the clutch elements between them. This delayed responsive action therefore advances the ring carrying member by increments of its rotary movement within the cylinder which is less than the full rotation which should have been imparted to it by the control means whereby the ring carrying member traverses a slightly different rotary and rectilinear path as it moves within the cylinder operated upon.

In operating the machine a new or replacement set of rings 6 are fitted in the grooves 24 of the ring mounting member 22. The motor cylinder 1 in which said rings are to be used is then clamped to the standard 10 on the machine base by means of the clamps 14. The length of the particular stroke for the cylinder is then determined by adjustment of the stops 61 and 62 on the control rod 60. The hydraulic system is then put in operation and its reciprocating speed adjusted by means of the control valve 54 and said motor will then reciprocate the rings within the cylinder 1, the clutches serving to permit rotation of said ring carrying member during the feed stroke and to impart to the ring carrying member a non-rotary return stroke. This reciprocation is continued until the rings have been lapped to exactly fit the cylinder 1.

What is claimed is:

1. In a machine of the class described the combination of a base, a ring carrying member, means for reciprocating the member, a control means rotatably mounted on the base for journaling the member, means interposed between the base and the control means for locking said means upon movement of the member in one phase of its reciprocation, and means responsive to the return stroke movement of the member for rendering the control means inoperative.

2. In a machine of the class described the combination of a base, a threaded ring carrying member, means for reciprocating the member, a threaded sleeve rotatably mounted on the base and slidably mounting the threaded portion of the member, clutch means for locking the sleeve against rotation in one phase of the reciprocating movement of the member, and a second clutch means for locking the member against rotation in the opposite reciprocatory phase.

3. In a machine of the class described the combination of a base, a threaded ring carrying member, means for reciprocating the member, a threaded sleeve rotatably mounted on the base and slidably mounting the member, clutch means responsive to the movement of the member in one phase of its reciprocation for locking the sleeve against rotation, and a second clutch means responsive to the movement of the member in its opposite reciprocatory phase for locking the member against rotation.

4. In a machine of the class described the combination of a base, a threaded ring carrying member, means for reciprocating the member, a threaded sleeve rotatably mounted on the base and slidably mounting the threaded portion of the member, an over-running clutch means interposed between the sleeve and the base and actuated to lock the sleeve against rotation only upon movement of the member in one phase of its reciprocating movement, and a second over-running clutch means interposed between the base and the member and actuated to lock the member against rotation only upon movement of the member in the opposite phase of its reciprocatory movement.

5. In a ring lapping machine for motor cylinders the combination of a base, a bearing block on the base, a threaded sleeve rotatably mounted in the block against axial movement, a threaded shaft slidably engaged by the sleeve and mounted thereby for axial movement relative to the base, means for imparting an alternate succession of feed and return strokes to the member, a standard on the base for mounting a cylinder in coaxial alignment with the shaft, a ring mounting member fixed coaxially on the end of the shaft and movable within the cylinder, a first over-running clutch means interposed between the sleeve and the base and actuated to lock the sleeve against rotation only during the feed stroke of the shaft, and a second over-running clutch means interposed between the base and the shaft and actuated to lock the shaft against rotation only during the return stroke of said shaft.

6. In a ring lapping machine as set forth in claim 5 wherein the first over-running clutch means comprises a clutch plate fixed to the block and having a circular opening disposed coaxially with the sleeve, a clutch race keyed to the sleeve and rotatable in the opening, a restricted passageway formed between the race and the plate, a clutch element in the passageway, and means for urging the element toward the restricted portion of the passageway.

7. In a ring lapping machine as set forth in claim 5 wherein the second over-running clutch means comprises a concentric circular portion formed on the end of the shaft, a clutch plate having a clutch race opening formed therein for rotatably receiving the circular portion of the shaft, means for precluding axial movement between the plate and the shaft, a guide rod on the base disposed parallel to the shaft, an arm on the plate for freely engaging the rod, a restricted passageway formed between the circular portion of the shaft and the opening in the plate, a clutch element in the passageway, and means for urging the element toward the restricted portion of said passageway.

CHARLES A. FULMER.
